UNITED STATES PATENT OFFICE.

LEONARD J. FILITTI, OF ALBANY, NEW YORK.

ELECTRIC TRAIN CONTROL.

1,141,953.

Specification of Letters Patent. Patented June 8, 1915.

Application filed March 17, 1914. Serial No. 825,313.

To all whom it may concern:

Be it known that I, LEONARD J. FILITTI, a citizen of the United States, residing at Albany, in the county of Albany and State of New York, have invented new and useful Improvements in Electric Train Controls, of which the following is a specification.

The invention relates to an electric train control, comprehending particularly a means whereby the train in the predetermined position in the block will energize certain signals for a following or approaching train and will simultaneously energize the track elements which will automatically control the following or approaching train.

The main object of the present invention is the provision of a track provided with contact sections for the control of the signals and with contact shoes arranged between the rails which are energized in the automatic energization of the system, combined with means controlled by the contact sections for actuating the signals and means controlled by the contact shoes for governing the travel of the train.

The invention in the preferred form of details will be described in the following specification, reference being had particularly to the accompanying drawings, in which:

Figure 1 is a diagrammatic view illustrating the application of the system, a signal block only being shown. Fig. 2 is an enlarged diagrammatic view illustrating particularly the means for controlling the travel of the train. Fig. 3 is an enlarged sectional view through the casing showing the means for controlling the signal switches. Fig. 4 is section on line 4-4 of Fig. 2. Fig. 5 is a section on line 5-5 of Fig. 2. Fig. 6 is a diagrammatic view illustrating the contact wheels carried by the locomotive. Fig. 7 is a broken elevation of one of the moving rails showing the application thereto of the contact section.

Referring particularly to the accompanying drawings, the improved system is provided with rails 1 and 2 of the trackway and with what I will hereinafter term the contact sections. These sections which are insulated from the rail, are set into the rail so as to form in effect a part of the tread portion thereof, as clearly shown in Fig. 7. Two of such sections are arranged at the respective ends of the block on the rail 1, said sections being hereinafter denoted as 3 and 4, 5 and 6. One of such sections is lo-

cated at each end of the block on the rail 2, such sections being referred to hereinafter as 7 and 8. The sections 7 and 8 are of greater length than the remaining sections 60 and are preferably arranged in the rail 2 beyond the opposing two sections of the opposite rail. Therefore at each end of the block there are three contact sections, two in one rail and one in the other, it being understood of course that so far as the described control is concerned each block is complete in itself and constructed in accordance with the description herein. Intermediate the rails 1 and 2 at the end of each 70 block are a pair of contact shoes, said shoes being of considerable length and being wholly free of electrical connection with the sections. In the block shown the shoes at one end are numbered 9 and 10 and at the 75 opposite end 11 and 12.

Line wires 13 and 14 extend lengthwise the trackway to be protected, said wires being energized from any suitable source and constitute an opening circuit extending 80 throughout the length of such trackway. At an appropriate point in each block is arranged a casing 15 within which is mounted signal control apparatus, and while I have shown and will describe a preferred type of 85 such apparatus, it is to be understood that I contemplate any accepted electrical or mechanical equivalents for the details shown. Within the casing is mounted a shaft 16 geared to opposing motors 17 and 18 adapted to reversely actuate the shaft in their respective energizations. Secured upon the shaft 16 is a controlled disk 19 connected to opposing links 20 and 21 to signal controlled switches 22 and 23. The switch 22 is a three 95 plate switch, while the switch 23 is a two plate switch. The links 20 and 21 are so connected to the disk that in the rotation of the latter under the influence of the motors, the switches are reversely operated, 100 that is one is closed, while the other is open.

To prevent overturning of the disk, the latter is provided with projections 24 to which are loosely connected rods 25 adapted to pass through openings in the bar 26 fixed 105 in the casing, the rods being headed below the bar. By this means the movement of the disk in either direction is limited to just insure a full closing of the particular switch being operated. At the respective ends of 110 the block are arranged signals of any preferred type, illustrated in the present in-

stance as incandescent lamps, the signals including danger signals 27, caution signals 28 and clear signals 29. The respective signals at each end of the block are in circuit, 5 that is the clear signals 29 are in circuit through conductors, 30, the caution signals 28 are in circuit through conductors 31, and the danger signals 27 are in circuit through conductors 32. Furthermore, the caution 10 signals at one end of the block are in circuit through conductors 33, 34, with the clear signals of the next block in rear. The respective points of the switch 22, as 35, 37 and 36 are in circuit with the signals, the 15 points 35 and 36 being in circuit with the caution signals, that is the conductors 31, while the point 37 is in circuit with one of the conductors 30, the opposing conductor 30 leading to the caution signal of the block 20 in advance as previously explained, that is continued as conductor 33, the return conductor 34 of such caution signal, of the block in advance leading to the blade 38 of the switch 22, which coöperates with the point 25 37. The blade 39 of the switch 22 which coöperates with the point 36 is in particular circuit through a conductor 40 with one of the mains, as 13, while the blade 41 of the switch 22 is in circuit through a conductor 30 42 with the remaining main 14. The respective blades 43, 44, of the switch 23 are in circuit by conductors 45, 46 with the respective mains 13 and 14, and the points 47, 48 of such switch 23 are in circuit 35 through conductors 49 and 50 with the contact shoes 11 and 12. The shoes 11 and 12 are respectively in electrical connection through track wires 51, 52 with the shoes 9 and 10 at the opposing ends of the block. 40 The conductors 32 of the danger signals are in electrical connection with the conductors 49 and 50 through conductors 53, 54, so that when the switch 23 is closed the energy of the mains is utilized in the danger signal 45 circuit, as well as for energizing the contact shoes 9, 10, 11 and 12.

The contact sections 3 and 6 are through conductors 55 and 56 in electrical connection with the conductor 57 leading to one side of 50 the motor 17, which motor it will be understood controls the switch 22, while the contact sections 4 and 5 are through conductors 58 and 59 in electrical connection with the conductor 60 leading to one side of the motor 18, which it will be understood, controls the switch 23. The sections 7 and 8 are through conductors 61 and 62 in electrical connection with the main or line wire 14.

Arranged in the train are contact wheels 55 63, 64 in electrical connection through conductors 65, 66 preferably joined by plug and socket connection to permit their separation when desired. The wheels 63, 64, which constitute the contact wheels, are fixed with 66 respect to their position on the locomotive

and to each other, and are so located that when one of the wheels is in contact with the section 5 for example, the opposing wheel will be in contact with the section 8. The wheels operate in the nature of the moving 70 switch to complete the various circuits as the train advances, as will later appear.

An additional set of contact wheels 67, 68, insulated from each other, are mounted on an appropriate part of the train structure 75 for coöperation with the contact shoe, the former set of contact wheels 63, 64, being hereinafter referred to as signal contact wheels, while the latter set 67, 68 are hereinafter referred to as the control contact 80 wheels. Mounted at an appropriate point on the locomotive is a motor 69 electrically connected through conductors 70, 71 with the respective contact wheels 67, 68. The motor is connected through a suitable 85 sprocket 72 and chain 72' with the peripheral toothed disk 73 which disk has eccentrically connected thereto link 74 connected through the medium of the rod 75 with the roller 76 adapted for travel in upper and lower guide- 90 ways 77 fixed on the locomotive. A chain or other flexible connection 78 is fixed to the roller axle and to the valve lever 79 adapted in operation to vent the train pipe 80 to set the brakes. The disk 73 has an 95 opposite hub 81 to which is secured one end of the flexible connection 82 adapted to pass over the idler 83 and terminally connected to the locking dog lever 84 and by the medium of such connection to the throttle lever 100 85. Therefore as the disk 73 is operated, the train pipe is vented and the throttle lever shifted to cut off the power. An auxiliary signal circuit is arranged in the locomotive including conductors 86, 87, in circuit with 105 the conductors 70 and 71 and leading through an appropriate switch 88 to the signal such as a lamp 89. The switch 88 operates to cut off the power from the contact shoe to the motor 69 and allows the engineer to turn on power and release the 110 brakes when the contact wheels 67, 68 are in contact with the shoes 9 and 10 or 11 and 12. If preferred, the shaft 16 may be provided with a belt connection 90 for the operation of the superimposed shaft 91 carrying the semaphore or other signal alarm 92.

In operation, it will be understood that the switch 22 is normally closed, so that the clear and caution signals are energized in 120 each block, this condition indicating an absolutely clear track. A train entering the block will cause the signal contact wheels 63, 64, to simultaneously engage the contact sections 5 and 8. This completes the circuit 125 through the line wires 13 and 14, and the motor 18, the circuit being line wire 14, section 8, wheel 64, conductors 66, 65, wheel 63, section 5, conductor 59, conductor 60, motor 18 and the conductor from the motor to the 130

line wire 13. 22 opens and the switch 23 is closed. By the closing of the switch 23 the danger signals 27 are energized and the shoes 9, 10, 11 and 12 also energized. If at 5 this time a train is in electrical contact with the remote pair of shoes of the adjacent block, a circuit is completed through the respective contact wheels 67, 68 of the locomotive with the effect to energize the signal 10 89. If the engineer does not promptly control his train in response to such signal, continued operation of the motor 69 will close the throttle and set the air brakes. As the 15 particular train moves out of the block the wheels or signal contacts 63, 64 will engage the sections 3 and 7, completing the circuit and the motor 17 and closing the switch 22 and opening the switch 23. This operation 20 reenergizes the caution and clear signals of the block and cuts out the danger signal. As the particular train reaches the sections 25 5 and 8 of the next block and operates or opens the switch 22 thereof such switch braking continuity of the caution signal circuit of that block will simultaneously break the circuit including conductors 33, 34, reaching back to the clear signal of the preceding block. The clear signal will be extinguished, leaving the caution signal visible 30 until the particular train has reclosed the switch 22 of that particular block, which will clear up the preceding block by restoring the clear signal thereto.

It will be apparent from the above description that I have provided a means whereby the signals are automatically controlled by the traveling train and at the same time an independent control system is automatically energized to take care of an 35 advancing or following train.

What is claimed is:—

1. A track arranged in blocks, a series of

signals including a clear lamp, a caution lamp, and a danger lamp arranged at the terminal of each block, mains energized 45 from a remote source, conductors leading from the mains to each of said signals of each series, a switch simultaneously controlling the clear and caution signals of each series, a second switch controlling the danger signal of each series, and opposed motors for actuating the switches and track carried contacts at the respective ends of the blocks electrically connected to and controlling said motors, the clear lamp of one 50 block being in series with the caution lamp of the block in advance.

2. A track arranged in blocks, a series of signals including a clear lamp, a caution lamp, and a danger lamp arranged at the 60 terminal of each block, mains energized from a remote source, conductors leading from the mains to each of said signals of each series, a switch simultaneously controlling the clear and caution lamp of each series, a second switch controlling the danger signal of each series, and opposed motors, links connected thereto for actuating the switches and contacts at the respective ends of the blocks for controlling said motors, 65 control means carried by the track traveling vehicle, spaced contacts arranged between the tracks and normally energized from the mains, and circuit closing elements carried by the vehicle and engaging said 70 last mentioned contacts to operate the train control means.

In testimony whereof I affix my signature in presence of two witnesses.

LEONARD J. FILITTI.
